CLAIM

The ornamental design for a temperature monitoring buffering sensor, as shown and described.

DESCRIPTION

FIG. 1 is an isometric view of a temperature monitoring buffering sensor showing the new design;

FIG. 2 is a bottom view thereof;

FIG. 3 is a top view thereof;

FIG. 4 is a left side elevation view thereof;

FIG. 5 is a right side elevation view thereof;

FIG. 6 is a front elevation view thereof; and,

FIG. 7 is a bottom view thereof.

The features shown in broken lines are included for the purpose of illustrating portions of the temperature monitoring buffering sensor and form no part of the claimed design.
